DESIGN FOR A TRAY

Frederick Henry Berlin, Jr., New York, N. Y.

Application June 29, 1946, Serial No. 131,193

Term of patent 3½ years

(Cl. D44—10)

To all whom it may concern:

Be it known that I, Frederick Henry Berlin, Jr., a citizen of the United States of America, residing in the city, county, and State of New York, have invented a new, original, and ornamental Design for a Tray, of which the following is a specification, reference being had to the accompanying drawings forming part thereof, wherein:

Fig. 2 is a side elevational view of the tray of Fig. 1; and

Fig. 3 is an end elevational view of the tray of Fig. 1.

I claim:

The ornamental design for a tray, as shown.

FREDERICK HENRY BERLIN, JR.
